(57) **CLAIM**

The ornamental design for a protruding camera, as shown and described.

DESCRIPTION

FIG. 1 is a front perspective view of a protruding camera, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the protruding camera, which form no part of the claimed design.

The protruding camera is shown with symbolic breaks, formed by dash-dot-dash broken lines.

The appearance of any portion of the article between the break lines forms no part of the claimed design.
